UNITED STATES PATENT OFFICE.

JOHN POWER, OF PUEBLO, COLORADO.

INGOT-MOLD.

1,036,333.

Specification of Letters Patent. Patented Aug. 20, 1912.

Application filed June 1, 1912. Serial No. 700,994.

To all whom it may concern:

Be it known that I, JOHN POWER, a citizen of the United States, residing at Pueblo, in the county of Pueblo and State of Colorado, 5 have invented certain new and useful Improvements in Ingot-Molds, of which the following is a specification.

My invention relates to ingot molds for casting steel ingots and particularly to a 10 mold having a double shell.

The inner walls of a mold are worn quite rapidly by the action of the molten metal and alternate expansion and contraction to which it is subjected, so that the mold becomes 15 missshapen or otherwise unsatisfactory in a short time and must be discarded.

The object of my invention is to provide a mold in which an inner separable portion is subjected to the wear and deterioration 20 of the casting operation while the outer portion or jacket may be used repeatedly by renewing the inner lining or casting member. These and other objects will be understood from the following description in 25 connection with the accompanying drawings, in which—

Figure 1 is a vertical section of a molding apparatus showing the manner of casting the inner lining member of my ingot mold 30 within the outer jacket; Fig. 2, is a vertical section of the same at right angles to the plane of Fig. 1; Fig. 3, is a vertical section of my double-shelled ingot-mold; Fig. 4, is a side elevation of the mold in a plane at 35 right angles to Fig. 3; Fig. 5, is a vertical section of my mold showing the manner of removing the inner lining or casting-member; Fig. 6, is a top plan view of the mold; Fig. 7, is a top plan view of a mold having 40 a split outer jacket; Fig. 8, is an enlarged cross-section on the line 8—8 of Fig. 3; and Fig. 9, is a bottom plan view of the mold.

The outer steel jacket 1 is first cast in the usual manner, being provided with ears or 45 lugs 2, by which it may be lifted to strip the mold from the ingot. I also provide an enlargement or recess in the bore at the bottom with an overhanging ledge 4 along the sides as shown in Figs. 3, 5 and 8.

50 After the jacket 1 has been properly cleaned, it is placed over a sand-core 6, having the form of the steel ingots desired. The bottom of the steel jacket, which thus forms

the chill mold is surrounded by a cope 8 which is filled in with loam 9 to make a 55 tight joint, after which a cap 10 and filling rings 12, 14, are fitted over the top of the jacket and made fast by means of beams 15, bolted at 16 to the bottom or drag 18. A mold-cavity is thus formed between the 60 jacket 1 and the sand-core 6, which is connected by means of runner gates 20, with the runner spout 22. The molten iron or steel poured through the runner 22, passes upwardly, filling the mold-cavity between 65 the jacket 1, and the core 6, and flanging over the top of the jacket. The cast lining 24, thus formed is secured within the jacket by means of the flange 25 at the top and the flanges 27 at the bottom. After the lining 70 has solidified and cooled there will be a shrinkage space of about one-eighth inch between the lining and the jacket. After the duplex ingot mold thus formed has been removed from the core and casting apparatus, shown in Figs. 1 and 2, it is then in the form illustrated in Figs. 3 and 4, and, 75 after being cleaned is ready to be used for casting steel ingots.

As I have previously pointed out, the interior wall or cavity of the ingot mold is rapidly worn by the action of the molten metal poured therein, so that an ordinary mold is soon worn out or rendered unsatisfactory. By my present invention, a 80 duplex shell is provided constituting a duplex mold, and the wear is principally upon the inner lining or casting member 24.

In order that the inner lining member may be readily removed from the outer 90 jacket when it becomes worn, I preferably form a weakened line or line of cleavage or demarcation 30, at the base of the flange 25, so that the flange may be easily severed. To effect a separation of the outer jacket, 95 the outer jacket may be supported upon an annular base 32, under a drop-hammer, and a blow from the latter upon the lining member 24, within the line of demarcation will sever the flange 25 as shown in Fig. 5, and 100 permit the jacket to be lifted clear of the lining. A new lining may be then cast in the jacket in the manner previously described.

While I have described the particular construction illustrated in the drawings for 105

the purpose of disclosing an embodiment of my invention, it will be obvious to engineers that various changes may be made therein without departing from the spirit of my invention.

5 I claim:—

1. An ingot-mold, comprising an outer jacket and an inner lining or casting-member cast into locked relation therewith.
- 10 2. An ingot-mold, comprising an integral outer jacket and an inner lining, or casting-member having flanges locking the outer and inner members together until said flanges are removed from the inner member.
- 15 3. An ingot-mold, comprising an outer jacket and an inner lining or casting-member having a flange extending over the top of the jacket, and a locking flange coöperating with the bottom of the jacket, one of

said flanges having a weakened joint at its 20 junction with the lining.

4. A duplex ingot-mold, comprising an integral outer jacket provided with a recess adjacent the lower end, and an inner lining member having a flange at its lower end 25 engaging said recess and a flange at its upper end extending over the jacket and locking the lining thereto.

5. A duplex ingot-mold having outer and inner member being provided with an upper 30 marginal flange having a weakened portion or line of demarcation at its base.

In testimony whereof I affix my signature in presence of two witnesses.

JOHN POWER.
